(57) **CLAIM**

The ornamental design for a fishing rod support apparatus, as shown and described.

DESCRIPTION

FIG. 1 is a perspective view of the fishing rod support apparatus, showing the new design;

FIG. 2 is a front elevational view of the fishing rod support apparatus thereof;

FIG. 3 is a rear elevational view of the fishing rod support apparatus thereof;

FIG. 4 is a left side elevational view of the fishing rod support apparatus thereof;

FIG. 5 is a right side elevational view of the fishing rod support apparatus thereof;

FIG. 6 is a top plan view of the fishing rod support apparatus thereof;

FIG. 7 is a bottom plan view of the fishing rod support apparatus thereof; and,

FIG. 8 is an environmental view of the fishing rod support apparatus.

The broken lines in the drawings illustrate environmental subject matter and form no part of the claimed design.
